[57] CLAIM

The ornamental design for a timing light, as shown and described.

DESCRIPTION

FIG. 1 is a left side elevational view of a timing light showing our new design, the right side being a mirror image thereto;

FIG. 2 is a front elevational view thereof;

FIG. 3 is a top plan view thereof;

FIG. 4 is a bottom plan view thereof;

FIG. 5 is a rear elevational view thereof in a larger scale.

FIG. 2

FIG. 1

FIG. 3

FIG. 4

FIG. 5
